UNITED STATES PATENT OFFICE.

SIGMUND HOCHSTADTER, OF NEW YORK, N. Y.

DESIGN FOR A BOTTLE.

45,939.

Specification for Design.

Patented June 16, 1914.

Application filed April 9, 1913. Serial No. 760,047. Term of patent 14 years.

To all whom it may concern:

Be it known that I, SIGMUND HOCHSTADTER, a citizen of the United States, residing at Far Rockaway, in the city of New York, borough of Queens, Queens county, in the State of New York, have invented a new, original, and ornamental Design for a Bottle, of which the following is a specification, reference being had to the accompanying drawings, forming part thereof, and in which—

Figure 1 is a side view showing a bottle made according to, and incorporating my said design, and Fig. 2 is a top view thereof.

I claim:—

The ornamental design for a bottle as shown.

SIGMUND HOCHSTADTER.
